ALEXANDER GIRTANNER, OF ST. LOUIS, MISSOURI, ASSIGNOR OF ONE-HALF TO
JAMES A. DAVIESS, OF ST. LOUIS, MISSOURI.

ASH-CONVEYER.

1,096,623.

Specification of Letters Patent.

Patented May 12, 1914.

Application filed March 10, 1913. Serial No. 753,386.

To all whom it may concern:

Be it known that I, ALEXANDER GIRTANNER, a citizen of the United States of America, residing at the city of St. Louis, State of Missouri, have invented a certain new and useful Ash-Conveyer, of which the following is such a full, clear, and exact description as will enable any one skilled in the art to which it appertains to make and use the same, reference being had to the accompanying drawings, forming part of this specification.

My invention relates to an ash conveyer and consists of various novel features and details of construction, all of which are described in the following specification and pointed out in the claims affixed thereto.

In the accompanying drawings, which illustrate a conveyer made in accordance with my invention, Figure 1 is a side elevation on a reduced scale showing the complete conveyer; Fig. 2 is an enlarged section on the line 2—2 of Fig. 3; and Fig. 3 is a sectional view showing the point of junction between the inlet and discharge pipes.

Like marks of reference refer to similar parts in the several views of the drawings.

15 represents a furnace from which the ashes are to be conveyed. Adjacent to each 30 of the furnace doors is a hopper 16.

The various hoppers 16 are included in an inlet pipe 20 forming a portion of the conveyer tube. This inlet pipe 20 joins the discharge pipe 21 at an obtuse angle, as is best 35 shown in Fig. 3 of the drawings. These pipes are brought together at an angle for the purpose of providing an off-set through which a blower nozzle may be introduced into the pipe substantially in line with the 40 discharge pipe 21. In Figs. 2 and 3 of the drawings, the off-set 22 is provided with an opening 23 which is closed by a plate 24 held in position by bolts 25. Passing through an opening 26 in this plate 24 is a steam supply 45 pipe 27 upon the end of which is screwed a blast nozzle 28. This blast nozzle bears against the plate 24 and is held in position by means of a nut 29 placed around the tube 27 at the other side of the plate. The blast 50 nozzle 28 is slightly tapered and is provided on its interior with spirally arranged ribs

30 in order to give a twisting motion to the jet of steam as it escapes from the nozzle.

Beyond the point of junction of the pipes 20 and 21, I provide an expansion chamber 40, best shown in Fig. 3. This expansion chamber 40 is entirely unobstructed so as to allow the steam and ashes to become thoroughly mixed at this point. This chamber 40 is also provided, on its interior, with 60 spiral ribs 41 to impart rotary motion to the contents of the chamber as they pass through. The discharge pipe 21 terminates in a discharge nozzle 50 which projects into a suitable receiver 51 for receiving the ashes. 65

The operation of my conveyer is as follows: When it is desired to remove the ashes from any of the furnaces 15, the doors are opened to allow the ashes to drop in the hoppers 16. Steam is now admitted to the 70 nozzle 28 where it passes into the pipe 21. This steam carries along with it the air in the pipe 20 and thus causes a partial vacuum through which medium the ashes are drawn along the pipe 21 to a position in front of 75 the nozzle where they are carried out by force of the steam. The use of the unobstructed expansion chamber 40, together with the spiral ribs on the blast nozzle and on the expansion chamber causes the ashes 80 and steam to be thoroughly mixed and thus prevents clogging of the pipe.

Having fully described my invention, what I claim as new and desire to secure by United States Letters Patent is:

1. In an ash conveyer, the combination with an inlet pipe, of a discharge pipe joining said inlet pipe, and a blast nozzle substantially in line with said discharge pipe, said discharge pipe being provided with an 90 unobstructed expansion chamber adjacent to said blast nozzle.
2. In an ash conveyer, the combination with an inlet pipe, of a discharge pipe joining said inlet pipe, and a blast nozzle substantially in line with said discharge pipe, said discharge pipe being provided with an unobstructed expansion chamber adjacent to 95 said blast nozzle, said expansion chamber being provided with spiral ribs.
3. In an ash conveyer, the combination with an inlet pipe, of a discharge pipe join-

ing said inlet pipe, and a blast nozzle substantially in line with said discharge pipe, said blast nozzle being provided with spirally disposed ribs, said discharge pipe being provided with an unobstructed expansion chamber adjacent to said blast nozzle, said expansion chamber being provided with spirally disposed ribs.

In testimony whereof, I have hereunto set my hand and affixed my seal in the presence 10 of the two subscribing witnesses.

ALEXANDER GIRTANNER. [L. s.]
